UNITED STATES PATENT OFFICE.

MATHIAS MARX, OF NEILLSVILLE, WISCONSIN.

TRACE-COUPING.

1,098,817.

Specification of Letters Patent.

Patented June 2, 1914.

Application filed November 28, 1912. Serial No. 733,723.

To all whom it may concern:

Be it known that I, MATHIAS MARX, citizen of the United States, residing at Neillsville, in the county of Clark and State of Wisconsin, have invented certain new and useful Improvements in Trace-Couplings, of which the following is a specification.

This invention relates to improvements in harnesses, more particularly to the coupling means between the short or hame trace and the long trace and between the back band and the girth, and has for one of its objects to improve the construction and increase the efficiency and utility of devices of this character.

Another object of the invention is to provide a simply constructed device whereby the short trace and the long trace, the back band, the girth and the hold back portions of the harness are coupled and mutually supported by one single device, thus materially reducing the amount of material required in the harness.

With these and other objects in view the invention consists in certain novel features of construction as hereinafter shown and described and then specifically pointed out in the claim, and in the drawings illustrative of the preferred embodiment of the invention.

Figure 1 is an enlarged side elevation of the improved coupling or buckle frame. Fig. 2 is a side view of the parts shown in Fig. 1. Fig. 3 is a section on the line 4—4 of Fig. 2. Fig. 4 is a detail view of a supplemental strap and loop furnished with the device to enable it to be employed with harnesses of different forms.

Corresponding and like parts are referred to in the following description and indicated in all the views of the drawings by the same reference characters.

The improved device is designed to be used at the juncture of the short or hame trace and the long trace and the back band and girth portions of a harness and comprises in general an open frame including spaced longitudinally extending sides 10—11 and transverse bars 12—13 spaced apart with a flat loop 14 at one end and a semi-circular loop 15 at the opposite end. The transverse bars 12—13 are coupled by an intermediate longitudinal bar 16, the latter being provided with an outwardly directed stud 17. The side members 10—11 and the

outer portions of the loops 14—15 are in the same longitudinal plane, the bars 12—13 are slightly depressed or curved rearwardly, while the longitudinal bar 16 is depressed to a greater extent so that the outer terminal of the stud 17 comes substantially flush with the outer faces of the sides 10—11 and loops 14—15. Secured upon the side portions 10—11 of the frame is an outwardly curving bar 18, the latter being riveted or otherwise secured as shown at 19 to the side members of the frame. A lug 20 extends from the bar 18 and into the loop 15, and pivotally supported upon this lug is a stud 26 in which a ring 27 is mounted to swing, the ring designed to receive the forward end of one of the side straps, when required.

A portion of the billet of the back band of a harness is represented at 25 and extends beneath the side members 10—11 and 75 over the longitudinal bar 16 and engages with the stud 17 by one of a plurality of apertures represented at 28. By this means the back band is coupled to the buckle frame and is adjustable therein within the range 80 of the apertures 28.

The hame tug or trace is adapted to be engaged at its rear end with the loop 14. The long trace is adapted to be connected at its forward end in the ordinary manner to 85 the loop 15 of the buckle frame. A portion of the hold back strap is represented conventionally at 33 and passes between the main buckle frame and the outwardly curving bar 18 and thence to the coupling portions of the hames. By this simple means it will be obvious that the parts are effectually coupled and prevented from displacement and the amount of material required materially decreased with the increase of weight. 95 The cost of manufacture is also thus effectually decreased as a much less quantity of leather is required in the improved construction without decreasing the efficiency or strength.

When the form of back band billet 25 shown in Fig. 1 is not employed a short section of a strap 40 is employed in place thereof and with a D ring 41 at the lower end to receive the billet portion of the girth 105 while the back band billet is buckled to the member 40 in the ordinary manner.

Having thus described the invention, what I claim is:

In a buckle, a frame including end and 110

side members, a bar connecting the end members and curving away from the same and having an inwardly directed stud, and a guard connected to the side members and 5 extending at right angles to the bar and spaced from the same and likewise extending over the stud and spaced therefrom, said bar adapted to support a strap and through which the stud is adapted to extend and the

guard adapted to receive another strap and 10 adapted to hold the same against the stud.

In testimony whereof I affix my signature in presence of two witnesses.

MATH. MARX. [L. S.]
